MOBILE SERVING UNIT

Marvin E. Garfinkle, 599 Alta Vista Way,
Laguna Beach, Calif.

Filed July 16, 1962, Ser. No. 70,951

Term of patent 3½ years

(Cl. D14—3)

The rear not shown is substantially plain except for the conventional bracket shown in broken lines.

I claim:

The ornamental design for a mobile serving unit, substantially as shown and described.
